[57] CLAIM

The ornamental design for a sole plate for a shoe, as shown and described.

DESCRIPTION

FIG. 1 is a bottom plan view of a sole plate for a shoe showing my new design;

FIG. 2 is a side elevational view of one side of the sole plate shown in FIG. 1;

FIG. 3 is a side elevational view of the other side of the sole plate shown in FIG. 1;

FIG. 4 is a front elevational view of the sole plate shown in FIG. 1; and

FIG. 5 is a rear elevational view of the sole plate shown in FIG. 1.

The top surface of the sole plate is substantially plain.

FIG. 1.

FIG. 2.

FIG. 3.

FIG. 5.

FIG. 4.
